WIRELESS TRANSMITTER HOUSING

Paul E. Richards, Los Angeles County, Calif., assignor to
Audiodyne Corporation, Northridge, Calif., a corporation of California

Filed May 13, 1968, Ser. No. 11,901

Term of patent 14 years

Int. Cl. D14—03

U.S. Cl. D26—14

FIGURE 1 is a top plan view showing my new design for the wireless transmitter housing;

FIGURE 2 is a side elevational view thereof;

FIGURE 3 is an elevation as seen from the left of FIGURE 2;

FIGURE 4 is a side elevational view thereof;

FIGURE 5 is a bottom plan view thereof; and

FIGURE 6 is an elevation as seen from the right of FIGURE 2.

I claim:

The ornamental design for a wireless transmitter housing, substantially as shown.
